UNITED STATES PATENT OFFICE.

STOCKTON BORTON, OF PHILADELPHIA, PENNSYLVANIA, AND CHARLES H. WILLCOX, OF NEW YORK, N. Y., ASSIGNEES TO THE WILLCOX & GIBBS SEWING MACHINE COMPANY, OF NEW YORK, N. Y.

SEWING AND TRIMMING MACHINE.

SPECIFICATION forming part of Letters Patent No. 275,981, dated April 17, 1883.

Application filed December 27, 1882. (No model.)

To all whom it may concern:

- Be it known that we, STOCKTON BORTON, of Philadelphia, in the county of Philadelphia and State of Pennsylvania, and CHARLES H. WILLCOX, of New York, in the county and State of New York, have invented a new and useful Improvement in Sewing and Trimming Machines, which improvement is fully set forth in the following specification.
- 10 This invention has reference more particularly to machines for simultaneously sewing and trimming knit goods and other fabric, but is in part applicable to sewing-machines generally.
- 15 It consists, first, in the combination, with a sewing-machine having an under feed and trimming attachment therefor, of means for relieving at each descent of the needle the pressure of the presser-foot, so that the machine
- 20 may sew and trim around small circles—such, for example, as the ends of glove-fingers.

The second part of the invention comprises certain improved means for automatically relieving the pressure of the presser-foot. A 25 vibratory lever or other suitable reciprocating piece acts upon the presser-foot through a spring which serves as the medium of communication, and through which a continuous and unbroken connection is maintained. The use 30 of contact devices or stops is avoided, (the vibratory lever or reciprocating piece being disconnected from the presser-foot, except through the continuous elastic connection,) so that the hard and noisy action due to the rapid striking of surfaces is avoided. The spring is compressed on the ascent of the needle-bar, so as to force down the presser-foot at the time of 35 the feed, and is allowed to expand on the ensuing descent of the needle, so as to allow the 40 fabric to be turned while the needle is in the work. This portion of the invention comprises, also, certain other constructions and combinations of elements, which will be hereinafter fully set forth.

45 The third part of the invention comprises improvements in the trimming attachment—to wit, in the mechanism for automatically clamping the work for a short time at each stitch, so as to hold it stationary while the trimmer is cut-

ting, and then to relieve it while the feed takes 50 place, and also in the means for adjusting the position of the upper shear-blade of the trimmer and of the clamping-finger relatively to the stitch-forming devices, or, in other words, for regulating their distance from the line of 55 seam.

The improvement in the clamping mechanism consists in operating the clamping device or finger through an elastic lever-arm or flat spring connected at one end to a rock-shaft 60 which carries the clamping device or finger, and at the other to an eccentric-strap or other reciprocating piece. Preferably the spring is connected with the same strap which operates the upper shear-blade of the trimmer, but not 65 necessarily so, since it can be operated by a separate eccentric and strap, or from some other part of the sewing-machine or trimming attachment. The principal advantage of this arrangement is that the pressure upon the 70 clamping-finger adjusts itself automatically to the thickness of the work beneath, being heavier as the work is thicker. It possesses advantage also in the way of simplicity, durability, and in the gradual application and release of the pressure, and, further, in permitting the degree of pressure to be readily adjusted by altering the position of the elastic arm relatively to the rock-shaft.

The improvement in the means for adjusting the position of the clamping device or finger and of the upper or vibratory shear-blade relatively to the stitching mechanism consists in adapting the rock-shaft and clamping device or finger carried thereby, to be adjusted 80 in the line of its (the said shaft's) length, and in connecting the said rock-shaft and that which carries the vibratory cutter or shear-blade, so that they are or may be moved together by one adjusting device. This part of 85 the invention may be considered as an improvement upon, addition to, or modification of the attachment described in Letters Patent No. 255,578, granted March 28, 1882, to the Willcox & Gibbs Sewing Machine Company 90 as our assignee.

The fourth part of the invention consists in combining with a trimmer or trimming attach-

ment a presser-foot having a hinge between the foot proper and the presser-bar, and so constructed as to allow the trimmer to operate alongside of the rear portion of the presser-foot; also, in combining the hinged foot with a clamping-finger so disposed alongside the hinge or rear portion of the presser-foot that a cutter may work between them; and, also, in the special construction of the hinge-joint so that the said joint and the spring connected therewith are protected from foreign matters, said spring being inclosed in the middle leaf of the hinge and bearing against a pin fixed in the outer leaves.

15 The fifth part of the invention consists in a special device for relieving at the will of the operator the clamp of the disk-tension on the thread—to wit, in a spring-plate having a small seat adapted, when forced between the tension-disks, to separate and hold them apart. Devices of various kinds have been made for this purpose, but it is unnecessary here to describe them.

In the accompanying drawings, which form a part of this specification, Figure 1 is a view in front elevation, partly in vertical longitudinal section, of a sewing-machine with trimming attachment, or a sewing and trimming machine, embodying the invention; Figs. 2 and 3, views 25 of the same in plan and end elevation, respectively, the end elevation partly in vertical cross-section; and Figs. 4 and 5 are views in plan and end elevation, respectively, of the trimming attachment, with a small part of the sewing-machine. Figs. 6 and 7 are enlarged views in vertical section, in planes at right angles to each other, of the hinged presser-foot detached. In Fig. 7 the presser-foot has a clamping-finger attached to it, which finger may be used 40 in place of the independent clamping device shown in the other figures. Fig. 8 is a detail view illustrating the device for relieving at will the tension; and Fig. 9, a similar view, showing the position of the cutter or blade 45 relatively to the needle.

A is the machine-frame, A² the main shaft, A³ the fly-wheel, A⁴ the looper or hook, A⁵ the needle-lever, A⁶ the needle-bar, A⁷ the presser-bar, and A⁸ the cloth-plate, all of the construction usual in the Willcox & Gibbs sewing-machine, or of any other ordinary or suitable construction.

The feed mechanism A⁹, as shown, embodies the improvements described in United States Letters Patent No. 255,577, granted March 28, 55 1882, to the Willcox & Gibbs Sewing Machine Company as our assignee; but feed mechanism of any ordinary or suitable construction may be used.

60 The disk-tension B, the intermittent tension B', the bar B², the pull-off B³, and the check-tension B⁴ are constructed and arranged as described in Letters Patent No. 255,581 to the same parties, on the same date. These may be replaced 65 by other suitable thread-controlling apparatus, if desired. The presser-foot B⁴ and the trimming attachment are constructed in the main

as described in Letters Patent No. 255,578, before mentioned, B⁵ being the trimmer-frame or frame of the attachment; B⁶, the stationary blade or adjustable cutter-bar; B⁷, the set-screw for holding the same in position; B⁸, the vibratory blade or cutter; C, the lever-arm; C', the link or eccentric-strap; C², the pin connecting the link or strap with the cutter-operating arm C and furnishing a long bearing, which permits the longitudinal adjustment of said rock-shaft; C³, the eccentric fixed on shaft A²; C⁴, a spiral compression-spring encircling the rock-shaft B⁹ and tending to force it to the right, Fig. 1, so as to hold the edges of cutters B⁶ and B⁸ in contact with each other. C⁵ is a lever, which enables the operator to lift the presser-bar and presser-foot by means of a treadle connected with the right-hand end. The presser-bar A⁷ is connected by a screw with a plunger, C⁶, which is free to slide in a hole in the machine-frame, and which is pressed down by means of a spiral compression-spring, C⁷.

So far there is nothing new in the machine, and the brief description given, in connection with the drawings and the patents referred to, will suffice for a full understanding of the new 95 improvements, which will now be described.

Ordinarily the spring which depresses the presser-bar and presser-foot, and which is represented by the spiral spring C⁷, (although it may be and often is of a different construction,) 100 bears at its upper end against an adjusting screw or nut or a fixed portion of the machine-frame. In the present invention it bears against the lever-arm D through the intermediary of the pin C⁸ and disk C⁹ fixed thereon. 105 The pin C⁸ moves in guides in the machine-frame and in the plunger C⁶, and its upper end fits into a recess in the end of the lever-arm D. The lever-arm D is carried by a short shaft, D', journaled in the machine-frame, and 110 is operated from the needle-lever A⁵ through the arm D², fastened to the opposite end of the shaft D' and the link D³. At each vibration of the needle-lever, therefore, the lever D² D' D is vibrated also, and produces a reciprocation 115 of the pin C⁸ and disk C⁹. When the needle-bar rises the pin and disk are forced down by the lever-arm D compressing the spring C⁷, which thereupon communicates its pressure through the plunger C⁶ to the presser-bar and 120 presser-foot, so that the latter clamps the work with suitable pressure. When the needle-bar descends the lever-arm D, and the pin and disk C⁸ C⁹ rise and allow the spring C⁷ to expand and relieve the pressure of the 125 presser-foot upon the work, so that the latter can easily be turned. The parts are so disposed that when the spring C⁷ is expanded to its fullest extent it exerts little or no pressure. It is, however, often desirable that the work 130 should be relieved of the pressure due to the weight of the presser-foot and presser-bar, as well as of that due to any pressure of the spring. To effect this relief, an antagonistic spring, E,

is arranged to exert its force to lift the presser-bar. It is shown as a spiral compression-spring interposed between the fixed pin E' and the bottom of the plunger C⁶. The power thereof is less than that of the presser-spring C⁷, so that it does not prevent the presser-foot being held down by a suitable pressure; but it suffices to lift the presser-bar and presser-foot when the presser-spring C⁷ is expanded.

10 It is obviously desirable that the pressure with which the presser-foot is held down should admit of variation according to the nature of the work. The desired adjustment may be effected in various ways. As shown, 15 the connection between the lever-arm D² and the short shaft D' is made by a screw-clamp. By loosening said clamp and turning the shaft with the lever-arm D to the right or left the amount of compression of the presser-spring 20 C⁷, and consequently the pressure of the presser-foot upon the work may be regulated at will. It will be noticed that the pressure is gradually applied to and withdrawn from the presser-foot, and that the latter remains in contact with the work except for a very short 25 time at each stitch.

Referring now to the trimming attachment, F is a clamping device or finger for holding the work or fabric down upon the stationary 30 cutter bar or blade B⁶. It is carried by one end of a rock-shaft, F', journaled in the trimmer-frame B⁵. The opposite or right-hand end of the rock-shaft is connected by an elastic lever-arm, F², and a link, F³, with the pin C². 35 The arm F² is, as shown, a flat spring, which is at opposite ends screwed to the pieces F⁴ F⁵, the former, F⁴, having a hub by which it is attached to the rock-shaft F', and the latter, F⁵, recessed to receive the upper end of link 40 F³ and drilled and tapped to receive the screw-pin F⁶, by which said link is jointed thereto. The pin C² being reciprocated by the eccentric C³ through the link or strap C', the clamping device or finger F is at each stitch made to 45 press upon and clamp the work alongside the vibratory cutter B⁸. So soon as the finger or clamping device bears upon the work the elastic arm or spring F² bends and exerts its pressure thereon. The pin C² continuing its descent, the pressure is gradually increased until 50 the eccentric link or strap C' has passed the lower dead-point, when the pin C², rising gradually, withdraws the pressure, and after a while lifts the clamping device or finger clear of the work. The movement of the pin C² being the 55 same, the thicker the work between the clamping device and the cutter bar or blade B⁶ the more the arm or spring F² is bent, and consequently the heavier the pressure upon the work. The pressure can be adjusted at will 60 by altering the connection between the piece F⁴ and the rock-shaft F', the hub of said piece F⁴ being, as shown, clamped by a set-screw upon the rock-shaft so as to admit of the adjustment. The rock-shafts B⁹ F' are both adjustable lengthwise in their bearings, so as to bring the vibratory cutter or blade B⁸ and the

clamping device or finger F nearer to or farther from the needle. To adjust the position of both, the set-screw G is employed. This set-screw, which is parallel to the two rock-shafts, is tapped into the trimmer-frame and its end is split to cause it to retain the position at which it is set. Other means—such as a set-screw—could be used to retain it in position. 70 A radial flange, G', on said screw has its edge let into a notch in the hub of piece F⁴, so that the said piece, the rock-shaft F', and the clamping device or finger F follow the longitudinal motions of the set-screw. The flange also 75 forms a back-stop to the rock-shaft B⁹, so that it, with the vibratory cutter, also follows the longitudinal movements of the set-screw. Thus the vibratory cutter or blade and the clamping device or finger are or may be simultaneously adjusted nearer to or farther 80 from the line of stitching, and the clamping device or finger will always be, without care on the part of the operator, in the closest proximity to the vibratory cutter or blade in all 85 positions of the latter. A screw, G², tapped into the trimmer-frame and having its end inserted into a groove in the set-screw, limits the adjustment thereof in both directions. 90

The clamping device or finger is shown as 95 curved to clear the presser-bar; but, if desired, the presser-bar could be cut away instead. It is found advantageous in sewing around circles, particularly if of small diameter, to cut the fabric alongside the needle and not wholly 100 behind it. The vibratory cutter or blade is therefore extended, and in order that it may still cut in close proximity to the needle, the end is beveled or inclined to the vertical on the side adjacent to the needle. (See Figs. 4 105 and 9.)

In order that the cutters may not interfere with the turning of the work in sewing around small circles, the eccentric, which operates the vibratory cutter, and the clamping device or 110 finger are so set that the vibratory cutter rises slightly before the presser-foot resumes its hold on the fabric, while the needle is still in the work, and the body of the latter is entirely free. The vibratory cutter and the clamping 115 device or finger descend with the needle and rise with it. This is the most advantageous arrangement; but work can be performed with the parts differently timed.

The presser-foot B⁴ has been said to be in 120 the main like that shown in Patent No. 255,578; but it differs therefrom in having the foot proper (or the "sole," as it may be called) hinged, so that by working on the hinge it will allow 125 seams and thick places to pass without losing its pressure upon other parts of the work. The hinge, as shown, has its pivot at I, between the foot proper or sole and the portion I', which is fastened to the lower end of the presser-bar. The cutting portion of the trimmer is placed 130 at the side of the hinge or rear part of the presser-foot, so that when the latter is tilted by the passage of a seam the heel or rear part will maintain its pressure upon the work along.

side of said cutting portion, and will hold it firmly under the action of the trimmer. With the ordinary rigid foot the passage of a seam would lift the foot bodily, and for a time relieve the pressure alongside of the cutter, and thus lessen the efficiency of the trimmer.

- In order that cutters may work in close proximity to the line of stitching and to the needle, the presser-foot behind the needle is made 10 of half-width, and the plates $I^2 I^3 I^4$ of the hinge are made thin, so as to be contained in the space allowed. At the same time strength is given to the hinge by making the said plates deep. A spring, I^5 , is combined with the hinge. 15 It tends to keep the foot proper level while allowing it to tilt as occasion may require. To protect the spring, it is placed in an opening in the plate I^3 . Its free end acts upon the pin I^6 , fixed in the plates $I^2 I^4$.
- 20 To prevent foreign matter—such as lint and the like—working between the hinge-plates, the edges of these are curved at $I^7 I^8$ upon arcs struck from the pivot I as a center.

In putting the parts together the spring is 25 placed in its recess, the plates are interleaved, and the pivot-pin is inserted and secured. The free end of the spring is then pushed back by a small rod or wire inserted through the hole I^9 , and the pin I^6 is then fixed in position 30 in front of said end, and the rod or wire is removed. Space for the vibratory cutter B^8 is left between the clamping device or finger F and the rear part of the presser-foot. The hinged foot may be used with a clamping-finger attached to the foot proper, as shown at F^x , Fig. 7, or with one attached directly to 35 the presser-bar, as well as with an independent clamping device, as shown in the other figures; or it can be used in connection with trimming 40 attachments unprovided with clamping-fingers. It may be observed that hinged presser-feet have heretofore been used in sewing-machines, but never, so far as we are aware, in combination with a trimmer or trimming 45 attachment of any kind, nor of the construction stated.

In sewing it is very often desirable to release the tension upon the thread, so as to allow it to be drawn freely from the spool. For 50 this purpose the spring arm or plate H is employed. It is clamped between the base H' of the disk-tension, and is so bent that it naturally springs away from the tension-disks. Opposite the space between the tension-disks 55 is a small teat, H^2 . The operator, by pressing upon the upper end of the spring arm or plate H , (which is bent to allow his finger or thumb to rest more comfortably thereon,) forces the teat H^2 between the tension-disks, spreading 60 them apart and releasing their grip upon the thread. The automatic or intermittent tension B' of course releases the thread automatically at each stitch.

Modifications may be made in the details of 65 construction without departing from the spirit of the invention, and portions of the invention may be used separately. For example, the

means for relieving the pressure of the presser-foot could be used in sewing-machines not having a trimming attachment for sewing straw and for other purposes, or in machines having trimming attachments differing from that described; and so, also, the trimming attachment could be used independently. At the same time it should be understood that the machine shown embodies the invention in its best and most complete form.

It will be seen that the means for applying and releasing the pressure of the clamping device or fingers are analogous to those for 80 applying and releasing the pressure of the presser-foot, in that both apply and withdraw the pressure gradually through a spring from reciprocating or vibrating device without any striking of stops. So far as we are aware, the 85 combination of such means with a cloth or work clamping device in a sewing-machine (for the presser-foot is a clamping device as well as the clamping device or finger specifically so called) has never been before made, 90 and the combination broadly, as well as the special applications thereof is included in this invention.

Obviously the presser-spring could be made to bear directly against the movable device 95 for compressing it, instead of through the intermediary of a pin, as shown.

Having now fully described our said invention and the manner of carrying the same into effect, what we claim is—

1. The combination, with a sewing-machine having a four-motion under feed and provided with a trimming attachment, of mechanism for automatically relieving the pressure of the presser-foot while the needle is below the cloth-plate and the feed-surface depressed, and for restoring said pressure upon the rise of the needle and feed-surface, whereby the sewing and trimming around small circles are facilitated, substantially as described.

2. The combination of the sewing-machine, the trimmer carried by a stationary part of the machine—such as the cloth-plate—the automatic mechanism for relieving the pressure of the presser-foot on the descent of the needle and for restoring it on the ascent of said needle, and mechanism for operating the movable blade or cutter of said trimmer, substantially as described.

3. In a sewing-machine, the combination, 120 with the presser-foot and under feed, of mechanism comprising a reciprocating device and spring for automatically depressing the presser-foot on the ascent of the needle through the compression of said spring by said reciprocating device, and for relieving its pressure on the descent of the needle, substantially as described.

4. The combination, in a sewing-machine, of a cloth or work clamping device, a reciprocating piece, and an interposed spring through the medium of which pressure is conveyed to said clamping device from said reciprocating piece, the said clamping device, spring, and

- reciprocating piece being arranged, substantially as described, so that the pressure of the clamping device may be alternately applied and relieved without the striking contact of 5 rigid surfaces, as set forth.
5. The combination, with the presser-foot and needle-lever, of the vibratory lever, spring, and co-operating devices arranged to convey an intermittent pressure to the presser-foot 10 from the needle-lever through the spring, substantially as described.
6. The combination of the needle-lever, link, and vibratory lever with the presser-foot and intermediate devices, whereby the pressure of 15 the said foot is automatically relieved or withdrawn, substantially as described.
7. The combination, with the presser-foot, presser-spring, and movable part for automatically compressing and relieving said spring, of 20 the antagonistic spring, substantially as described.
- 25 8. The combination, with a clamping device, movable piece—such as an eccentric-strap, for example—and interposed spring, of adjusting means for varying the pressure without altering the movement of said piece, substantially as described.
- 30 9. The combination of the presser-foot, presser-spring, vibratory lever, link, and needle-lever, substantially as described.
- 35 10. The combination of the presser-foot, vibratory lever, presser-spring interposed between said lever and said presser-foot, and adjusting means for varying the pressure on said spring without altering the stroke of the lever, substantially as described.
- 40 11. The combination of the presser-foot, presser-spring, antagonistic spring, and vibratory lever, substantially as described.
- 45 12. The combination of the presser-foot, presser-spring, antagonistic spring, vibratory lever, and adjusting means, substantially as described.
- 50 13. The combination of the presser-foot, presser-spring, antagonistic spring, vibratory lever, link, and needle-lever, substantially as described.
- 55 14. The combination of the presser-foot, presser-bar, plunger, presser-spring, antagonistic spring, disk and pin, and vibratory lever, substantially as described.
- 60 15. In a trimmer or trimming attachment, the combination, with the clamping device or finger, of a movable piece—such as an eccentric-strap or a link—and a spring interposed between the said piece and the said clamping device or finger, and serving to communicate pressure from the former to the latter, substantially as described.
- 65 16. The combination of the clamping device or finger, the rock-shaft, the elastic lever-arm, and the movable piece—such as an eccentric strap or link—for operating on the end of said arm to rock said shaft, substantially as described.
17. The combination, with the trimming mechanism, of the clamping device or finger for clamping the work alongside of the cutting portion of the trimmer, a movable piece—such as the eccentric strap or link—the interposed 70 spring, and adjusting means for regulating the spring-pressure, substantially as described.
18. The combination of the clamping device or finger, the rock-shaft, the elastic lever-arm, the link or eccentric-strap and the eccentric, 75 substantially as described.
19. In combination with the two rock-shafts, the common eccentric and strap or link, the lever-arm for rocking one shaft, and the elastic lever-arm for operating the other, substantially 80 as described.
20. In combination with a rock-shaft, elastic lever-arm attached thereto and formed of a flat spring, the link connected with the outer end of said spring, and the reciprocating part, 85 with which the other end of said spring is connected, substantially as described.
21. The combination, in a trimmer, with the clamping device or finger, of the rock-shaft carrying said device or finger, and adjusting 90 means for moving the same longitudinally, substantially as described.
22. The combination, with the movable cutter or blade and the clamping device or finger, of adjusting means common to both for simultaneously adjusting them, substantially as described. 95
23. The combination, with the two rock-shafts capable of longitudinal adjustment, of the flanged set-screw connected with both for 100 adjusting them simultaneously, substantially as described.
24. The combination of the two rock-shafts, set-screw connected with both, and means for limiting the play of the set-screw, substantially 105 as described.
25. In a sewing and trimming machine, a vibratory shear blade or cutter arranged on the needle side of the line of trimming with its front end at the side of the needle, and 110 provided with a vertical bevel at said end on the face adjacent to the needle, in combination with a stationary shear blade or cutter arranged on the side of the line of trimming away from the needle and having its cutting-edge extended alongside of the needle, so that the said shear-blades may cut alongside the needle at a distance therefrom less than the thickness of the vibratory blade or cutter, substantially as described. 115
- 120 26. The combination, with the tension-disks, of a spring-arm provided with a teat for entering between and separating the said disks, substantially as described.
27. In a sewing and trimming machine, the 125 combination of the hinged presser-foot and the trimmer having its cutting portion at the side of the hinge or heel of the presser-foot, so that the said presser-foot at all times, during the passage of a seam, clamps the work alongside 130 said cutting portion, and thus assists the cutting operation, substantially as described.
28. The combination of the hinged presser-foot, the clamping-finger, and the cutter work-

ing between said finger and the hinge or rear part of the presser-foot, substantially as described.

29. A hinged presser-foot made of half-width 5 behind the needle, and having narrow and deep hinge-plates, in combination with a cutter arranged and operating alongside of said plates, substantially as described.

30. A hinged presser-foot having an inclosed 10 spring combined with the hinged joint, substantially as described.

31. The combination of the interleaved hinge-plates, inclosed spring, pivot-pin, and the pin 15 against which the spring presses, substantially as described.

32. The hinged presser-foot, comprising, in combination, an attaching portion, the foot proper, the interleaved hinge-plates having curved edges, the pivot-pin, the additional pin, and the inclosed spring, substantially as 20 described.

In testimony whereof we have signed this specification in the presence of two subscribing witnesses.
